(57) CLAIM

I claim the ornamental design for the combined beach bag and pillow, as shown and described.

DESCRIPTION

FIG. 1 is a perspective view of the combined beach bag and pillow;

FIG. 2 is a front elevational view thereof;

FIG. 3 is a rear elevational view thereof;

FIG. 4 is a left side elevational view thereof, the right side being a mirror image thereof;

FIG. 5 is a top plan view thereof; and,

FIG. 6 is a bottom plan view thereof.

In the drawings, the broken lines represent environmental structure forming no part of the claimed design.
